ANSON P. THAYER, OF SYRACUSE, NEW YORK.

Letters Patent No. 97,000, dated November 16, 1869.

IMPROVEMENT IN MACHINE FOR GRINDING THE CUTTERS OF MOWING-MACHINES.

The Schedule referred to in these Letters Patent and making part of the same.

To all whom it may concern:

Be it known that I, ANSON P. THAYER, of Syracuse, in the county of Onondaga, and State of New York, have invented new and useful Improvements in Machines for Grinding the Cutters of Mowing and Reaping-Machines; and I do hereby declare the following to be a full, clear, and exact description of the same, reference being had to the accompanying drawings, and to the letters and figures marked thereon.

The invention relates to that class of machines adapted for grinding the said cutters, whether in the machines to which they belong, or removed therefrom; and

It consists of a combination, on a stock or frame, arranged to be supported against the breast or other part of the person of the operator, and by one hand, of a grinding-stone or wheel-operating mechanism, and one or more adjustable guides or rests under an arrangement whereby the said stock or frame, being thus mainly supported, as above stated, may be more perfectly controlled and guided at the part supporting the stone, by the action of the said guides on the cutters or cutter-bars, while the said stone is operated against the bevelled edges of the cutters.

Figure 1 represents a side elevation of my improved machine, and

Figure 2 represents a plan view of the same, also a plan view of a part of the cutters and fingers or guards of a mower or reaper.

A is the stock, which may consist of a hollow tube, of metal or other suitable substance, or it may be a rod of iron, crotched for a suitable distance at one end, and provided with suitable bearings for the driving-shaft B, which, in this instance, is arranged in the bore of the tube.

The said stock A is provided with a breast-plate, C, at one end, and bent bars, D E, branching from the other, and at F it is notched or slotted in the sides, for the reception of the bevelled-toothed wheel, G, fixed to the shaft B, and gearing with the driving-wheel H, for which supporting stud-pins, I, are arranged on each side of the stock, on which the said wheel is fitted, so as to be readily changed from one to the other, whereby the operator may turn the wheel with either hand, no matter which side up the machine may be, the same being adapted for reversing its position in grinding the opposite edges of the cutters, as is required by the peculiar form of the said cutters.

K represents handles, by which the stock is held against the breast by one hand, one being provided for each side of the stock.

The bent branches D E are for the support of the mandrel L of the grinder M, carrying also the wheel

N, by which motion is communicated to the grinder from the wheel O on the shaft P, projecting out of the bore of the tube at the lower end. These branches or supports are so shaped, that while in the application of the machine to the cutters, the stock ranges in line with the edge being ground, as represented in fig. 2.

The mandrel L will stand parallel with the cutter-bar P, so that the plane of the stone will be such that the said stone may move up to the apex of the angle between the cutters.

Q is an adjustable gauge, consisting of a screw-threaded pin, screwing through a threaded hole in the bent branch E, in advance of the face of the stone, resting at its lower end on the upper face of the cutter being ground, or on the cutter-bar, for the purpose of providing a bearing to facilitate guiding and controlling the stone while grinding.

R is a similar guiding-pin, arranged in the same way in the branch D, or in a projection therefrom, and intended to bear on the face of the next cutter on the opposite side of the stock, the said branch or projection extending sufficiently to reach over the guard-finger, and beyond the same to the point on the said next cutter corresponding to the point on that one being ground, where the gauge Q bears. These points of bearing on the cutters are so calculated, in the arrangement of the branches by which the gauges are supported relatively to the stone, that in moving the stone along the edges of the cutters from point to heel, and *vice versa*, the said gauges, which similarly move on the cutters, will not come in contact with the fingers or guards S when the cutter-bar is adjusted in the machine, as represented in fig. 2, so as to present the cutters relatively, so that one edge of each cutter is uncovered by the guards.

I propose to use either one of these guide-pins, as may be found best in practice, and I propose, also, in some cases, to extend the branch E sufficiently to permit the pin Q to bear on the cutter next beyond the one being ground, on the same side of the stock.

The stone may have a face at right angles to its sides, or it may be bevelled, as represented in the drawing. I prefer, however, to have the bevelled face, for it permits the branches and mandrel to stand horizontally, whereas, if the face be at right angles to the sides, one side of the frame would have to stand higher than the other, which would interfere, to some extent, with the most advantageous working of the machine in respect to the driving-mechanism.

It will be seen, that to grind the opposite edges of the cutters, the machine must be worked one side up, with one set of edges, and the other side up, with the other set; also, that the stock must be presented in line with the edge to be ground, and from the rear side of the cutter bar. The end of the stock to be

applied to the breast may be more or less elevated, as preferred, so that the operator may either sit on a low bench, while holding the grinder on the cutters, while the same are in the mowing-machine, or he may kneel upon the ground.

The branched supports E D may, if preferred, be so pitched, relatively to the stock, that the latter may stand in other directions than in the line of the cutter-edge being ground; for instance, it may stand at right angles to the cutter-bar, and in line with, or parallel to the plane of the stone, but for guiding the stone over the cutter-edges while grinding, I prefer to have it in the direction stated.

The movement of the stone over the cutter-edges is effected by the operator swaying his body back and forth while holding the stone on the cutter, and turning the cranked driving-wheel H.

The ends of the guide-pins Q R may have friction-pads, of India rubber or any other substance which will lessen the tendency to slide on the faces of the cutters, whereby the machine will be more easily controlled. They may also be provided with jam-nuts, to secure them after being adjusted as required. They bear upon the cutters by one end, while grinding one set of edges, and by the other end, when grinding the other set, the machine being turned the opposite side up.

It will be observed that my improved machine differs from all others now in use, in the application to a frame or stock of a machine adapted for holding the stone in contact with the cutters, by means of a breast-stock and handle, of one or more guiding-pins, acting upon the cutters, or it may be other parts of the mowing or reaping-machine, whereby a more perfect control of the grinder is obtained.

Also, in the arrangement of the supports of the stone, and the stone, so that, while the stock is pitched in the line of the edges being ground, the plane of the stone bears such relation to the cutters and the fin-

gers or guards, that it will work up to the apex of the angle between the cutters, without interference with the edge opposite the one being ground, or down to the point, without interfering with the finger or guard, no matter what may be the diameter of the stone, whereby the movement of the stone over the edge to be ground may be effected wholly in one direction by the forward movement of the body, and in the other by the force of the hand in holding the stock against the breast, thereby giving the hand greater power to resist the lateral tendency of the machine, due to the action of the stone on the cutters, than can be had in any arrangement where the movement of the stone is in a direction laterally to the stock, in which case, both the movement of the stone and the lateral tendency of the stone in grinding must be controlled wholly by hand.

Moreover, by my arrangement, the action of the stone in grinding has much less tendency to carry the stock laterally, because the plane in which the stone works is nearer the line of the stock than at right angles thereto.

Having thus fully described my invention, What I claim, and desire to secure by Letters Patent, is—

1. The combination, with a grinding-stone and operating-mechanism arranged on a breast-stock, of one or more adjustable guides, arranged to bear and slide back and forth on the cutters or cutter-bar, substantially as specified.

2. The arrangement, with the breast-stock, of the supports for the stone-mandrel for maintaining the stock in line with the edge of the cutter being ground, while the plane of the stone is perpendicular to the cutter-bar, substantially as specified.

ANSON P. THAYER.
